[57] CLAIM

The ornamental design for a telephone set, as shown and described.

DESCRIPTION

FIG. 1 is a perspective view from the right side and above the top of a telephone set showing my new design;

FIG. 2 is a similar perspective view thereof with the handset removed for clarity of illustration;

FIG. 3 is a front elevational view thereof;

FIG. 4 is a top plan view thereof;

FIG. 5 is a rear elevational view thereof;

FIG. 6 is a left side elevational view thereof;

FIG. 7 is a right side elevational view thereof;

FIG. 8 is a bottom plan view thereof; and,

FIG. 9 is a left side view of a telephone set showing my new design rotated 90°.

Fig. 1.

Fig. 2.

Fig. 3.

Fig. 5.

Fig. 6.

Fig. 4.

Fig. 9.

Fig. 7.

Fig. 8.
